APPARATUS FOR COILING WIRE OR THE
LIKECarl O. Bruestle, Rahway, N. J., assignor to
Elevator Supplies Company, Incorporated,
Rahway, N. J., a corporation of New Jersey

Application August 10, 1938, Serial No. 224,037

8 Claims. (CL 242—82)

This invention relates to apparatus for coiling wire or the like, and provides improvements therein.

In the wire industry, wire of the larger sizes, as it comes from the wire drawing machine is usually wound or coiled on a drum, known as a "bull head," and the amount of wire taken up into the coil is determined by the size and capacity of the drum. Practical considerations, however, generally govern the amount of wire, or weight, in the coil. The weight of the coil is usually such that it can be handled by manpower. These coils are largely re-used in other wire drawing machines for drawing the smaller size wires. They are also a commodity, meeting the requirements of the market for bundles of limited weight, wire length, etc. This practice of coiling the wire from the wire drawing machines into coils of limited weight is generally followed, despite the recognized disadvantage of having to stop the machines after the completion of each coil. The stopping time is as much and usually considerably more than the running time.

The present invention provides an improved apparatus for coiling wire or the like which is continuous. It can, therefore, be used in an immediate succession to a wire drawing machine, without the necessity of repeated stopping and starting of the wire drawing machine. The wire from the wire drawing machine can be wound into coils or coil-bundles of desired weight and wire length, and removed, one after another, while the coiling apparatus runs continuously.

It has heretofore been proposed to coil wire continuously, removing the coils or coil-bundles one after another from the coiling apparatus, but such proposals, of which I know, leave much to be desired in the way of a satisfactory, efficient, safe and reliable apparatus.

The present invention provides an apparatus for continuously coiling wire or the like which has been demonstrated to operate successfully and satisfactorily to coil wire, which is strong and safe, and which operates efficiently and reliably.

In the coiling of wire, a high tension is imparted to the wire by the wire guide which revolves around the stationary drum on which the wire is coiled or wound. The stationary drum is supported with one end free so that the coils can be removed from and over its free end. The aforesaid winding tension produces a strong pull on the drum tending to rotate it, and it has been a problem to sustain such pull adequately and satisfactorily, and prevent the drum from being rotated. The present invention meets this

problem satisfactorily and effectively, the drum being secured against the pull of wire under high tension, while at the same time, coils wound on the drum may be efficiently and successively removed from the drum while the winding and coiling of the wire on the drum continues.

The invention further provides novel and advantageous structural arrangements and combinations hereinafter pointed out.

Two embodiments of the invention are illustrated in the accompanying drawings. The invention may, however, have other embodiments than those herein specifically illustrated and described.

Referring to said drawings:

Fig. 1 is a view in side elevation of one embodiment.

Fig. 2 is a vertical sectional view, on an enlarged scale, of a part of the structure illustrated in Fig. 1.

Fig. 3 is a top plan view of certain parts, including the wire guide, shown in Figs. 1 and 2.

Figs. 4 and 5 are respectively an end elevation, and a top plan view of the drum and parts associated therewith for holding it against rotation under the pull of the wire winding thereon.

Figs. 6 to 10 inclusive are diagrammatic views showing the coil at different stages of winding and removal.

Figs. 11 and 12 illustrate parts of a second embodiment, and showing the drum and certain associated parts in side elevation and top plan view respectively.

Fig. 13 is a sectional view illustrating in greater detail the mounting of the roller 62, Fig. 3.

Referring to said drawings, numeral 10 designates a stationary drum having a winding-on portion 12, and numeral 14 a rotary part having a wire guide 15 thereon, which revolves, when the rotary part 14 is rotated, around the winding-on portion 12 of the drum, coiling or winding the wire in successive spirals thereon.

The drum may be supported at one end, as indicated at 17, its other end 18 being free, so that wire coils may pass off from the drum, and be removed, as hereinafter more fully explained.

The rotary part 14 is rotatably supported in a suitable frame 20. As shown the frame 20 supports the drum 10 and rotary part 14 in a vertical position. This is advantageous, though the arrangement as to position may be otherwise.

In the illustrated form of embodiment, the rotary part 14 comprises a frame 22 of suitable construction, turning in suitable bearings. The rotary frame advantageously comprises an axial

sleeve 30, mounted in bearings 31, 32 on the stationary frame 20. An auxiliary bearing 26, which may comprise a track 28 and an encircling series of rollers 27 supported on frame 20, may be provided, if desired. Fixed on the sleeve 30 is a gear 35 through which the rotary part 14 is rotated. The gear 35 may be driven by a gear or worm 37 on a shaft 38, which shaft may be, as here shown, driven by an electric motor 40 mounted on the frame 20 of the machine.

The wire guide 15 advantageously comprises a sheave 45 turning on a pin 46 mounted on a bracket 48 fastened to the frame 22 of the rotary part 14. The bracket 48 is advantageously 15 a swivel connection to the frame 22. As here shown this may comprise a plate 51 having a pin 52 which fits in a hub 53 on the frame 22, and which pin may be fastened in different positions of adjustment by suitable means as a nut 54 and a set-screw 55. The bracket 48 is also advantageously adjustable as to its angular position. This angular adjustment may be provided by means of a slot 57 in the bracket 48 and bolts 58 and 59 passing through the plate 25 51 and bracket 48. This adjustability of the sheave 45 facilitates the running of the wire onto the sheave and from the sheave onto the winding-on portion 12 of the drum 10 at good angles. An auxiliary roller 62 is advantageously 30 employed as a part of the wire-guide. This auxiliary roller, as here shown, may be mounted on an arm 64 fastened or forming part of the rotary frame 22. The advantage of the auxiliary roller 62 is that it enables the sheave 45 to be 35 located closer to the axis of rotation of the rotary part 14 than would be the case without the auxiliary roller. Another advantage of the roller 62 is that by its use the diameter of the spiral of the wire may be varied. By substituting rollers 40 of different diameter the diameter of the spiral may be made greater or less, and the closeness with which the spirals, due to their form, hug or engage the winding-on portion 12, varied. The same thing may be accomplished by extending 45 the roller 62 toward or away from the axis of rotation of the rotary part 14, as shown in Fig. 13. This extension may be accomplished by mounting the roller 62 on a stud 65 which has an eccentric pin 66 which may be turned in a hole 67 in arm 64, to adjust the position of the roller 62, as just described. Means as a nut 68 and set-screw 69 may be provided for holding the pin 66 in a position of adjustment. The sheave 45, however, may be so arranged that the wire runs 50 directly from the sheave onto the winding-on portion 12 of the drum.

The wire is shown as entering the coiling apparatus at the lower right-hand side of Fig. 1. The wire may be coming directly from a wire 55 drawing machine running continuously, or from a reel. In passing to the drum 10, the wire, as here shown, may be led over a sheave 70, then over a sheave 72, which latter sheave has its periphery arranged tangentially to the axis of the bore 74 of the sleeve 30. The wire leaving the sheave 72 passes through the bore 74, then over a sheave 76 on the frame 22 of the rotary part, and thence to the sheave 45 of the wire guide 15. From the sheave 45, the wire may 60 either pass directly to the winding-on portion of the drum 12, or as here shown, over the auxiliary roller 62 and thence tangentially on to the winding-on portion 12 of the drum 10 as shown in Fig. 3. The wire passes around the winding- 65 portion 12 of the drum, in a sufficient num-

ber of spirals to provide a frictional resistance to the tension which is imparted to the wire by the revolving wire guide. The winding-on spirals of wire force those ahead of them off of the winding-on portion 12 of the drum, and the 5 spirals accumulate on the part of the drum beyond the winding-on portion 12, where coils or bundles are built up, and from whence the coils or bundles are removed, as will be hereinafter 10 more fully explained.

The wire which is bundled is usually a relatively thick or heavy wire, and the rotation of the rotary part 14 which carries the wire guide 15, tensions the wire highly and this results in a strong pull of the wire on the drum 10, tending to rotate it. Strong and firm means are required to resist the tendency of the drum 10 to 15 turn.

The drum 10 is advantageously supported by the rotary part 14, but in a manner that the 20 drum 10 is stationary while the rotary part 14 rotates. As here shown, the drum 10 has fastened thereto a shaft 80, which shaft 80 projects into a tubular part 82 of the rotary frame 22. Bearings 83, 84 are provided between the shaft 25 80 and the tubular part 82 of the frame 22, the bearings 83, 84, preferably being ball bearings, so that the rotary frame 22 and its tubular part 82 may turn with a minimum of resistance on the shaft 80. In the form of embodiment illustrated in Figs. 11 and 12, the axial support (shaft 80 and tubular-part 82) could be omitted.

For sustaining the pull of the wire on the drum 10, a plurality of detents 90, 92 are provided for 30 engaging the drum and holding it against rotation. The detents, as here shown, are advantageously in the form of jaws 100, 101 having flat faces 102, and the drum 10 is provided with flat faces 105, 106, or grooves having flat faces 105^a, 106^a, adapted to be engaged by the jaws 40 100, 101 of the detents 90, 92, each jaw being capable of strongly, adequately and reliably resisting the high tension of the wire exerted as a pull on the drum 10 tending to rotate the drum. The detents are suitably supported on the frame 45 20, and are arranged so as to be movable into and out of engagement with the drum, and are also spaced apart longitudinally of the drum 10 a distance sufficient to accommodate the number 50 of spirals which it is desired to build into a coil 55 or bundle of wire, or to feed off at one time.

The detents 90, 92 are also preferably provided with shelves 109, 110. The detents, jaws and shelves are advantageously in the form of a plate having wide portions around the jaw-recesses. The shelves 109, 110 in a vertical machine act to support the coils in a horizontal position. Suitable guideways 115, 116 on frame 20, on which the detents are slideable provide means for 60 slidably supporting the detents 90, 92.

Suitable means for moving the detents 90, 92 into and out of engagement with the drum 10 may be provided. These means, as here shown, may comprise motors 118 and 119 having a driving connection with the detents through pinions 121 and racks 123.

The arrangement and mode of operation of the detents 90, 92 is such that the detents may be moved alternately into and out of engagement with the drum 10. When, for example the detent 90, which is nearest the winding-on portion 12 of the drum is moved out of engagement with the drum, the coil resting above it on the shelf 109, can drop or move down toward the end of the drum, as far as the next detent 92 and come 70 75

to rest on the shelf 110 thereon. The detent 90 is then moved back so as to engage the drum. While resting on the shelf 110, a tie 113 of any suitable kind, as a piece of wire twisted at its ends, may be put around the coil, at one or more places, to bind the spirals together. From the shelf 110 the coil may be removed or dropped from the drum 10 by withdrawing the detent 92. At this time, as previously stated, the detent 90 is in engagement with the drum 10, and thereby serves to prevent turning of the drum while the detent 92 is withdrawn. Two detents 90, 92 are sufficient to allow the removal of a coil, while securely and strongly resisting the tendency of the drum 10 to turn, though a greater number of detents than the two shown can be used.

The coils, instead of forming individual and complete coils, may be increments which go to form a large coil off the coiling machine. The coils in the machine then would not be cut, and ordinarily the accumulation on the top shelf would be less, and the movement of the detents and shelves faster so as to pass off the accumulations (coil increments) more rapidly.

In practice, the alternate movements of the detents 90, 92 is effected automatically through suitable control means (not shown), which act to energize the motors 118, 119 at proper times, in proper sequence, and in the proper direction, to effect the movements of the detents 90, 92 related to the removal of a coil from the drum 10, already described.

In the embodiment illustrated in Figs. 11 and 12 each detent may be formed as complementary parts 90^a, 90^b, 92^a, 92^b. These complementary parts 90^a, 92^a, and 90^b, 92^b are arranged to move toward and from the drum 10 from opposite sides, as shown in Figs. 11 and 12. The jaw parts 90^a, 90^b, may be moved by one motor 118, into and out of engagement with the drum 10, in opposite directions, by suitable means as an endless chain 125. Similar movement is imparted to the complementary parts 92^a, 92^b of the detent 92 from motor 119 through an endless chain 127. The sequence of operation of the parts 90^a, 90^b of the detents 90, and the parts 92^a, 92^b of the detent 92 are essentially the same as that of the detents in the simpler form, already described. The complementary jaw-parts 90^a, 90^b, 92^a, 92^b also act to hold the drum against movement longitudinally and laterally of its axis, and thereby may serve to both support the drum and hold it against rotation.

With the drum 10 arranged with its axis vertical as shown in the drawings, it is advantageous to provide means to maintain at all times a certain or minimum number of wraps or spirals of the wire on the winding-on portion 12 of the drum. Suitable means for this purpose, as here shown, may have the form of one or more flanged rollers 130, two being here shown. These flanged rollers 130 may be mounted on arms 133, pivotally mounted on a part attached to the rotary frame 22, as for example a bracket arm 135 on the arm 64 which is attached to the said frame, and a bracket arm 137 attached to the said frame 22. Springs 140, act to draw the flanged rollers 130 toward the winding-on portion 12 of the drum, and against the wire thereon. The position of the flanged rollers 130 with relation to the longitudinal axis of the drum 10 may be, and preferably is, made adjustable. To this end, the arms 133, may be mounted on a threaded pintle 145 mounted on each of the bracket arms 135, 137. By turning the pintle

145 in one direction or the other, the height of the flanged roller 130 may be changed or adjusted. The number of wraps or spirals of wire on the winding-on portion 12 of the drum, may be regulated by the height or adjustment of the flanged rollers 130.

Operation

A strand of wire from a wire drawing machine, (or it may be from a large reel of wire) enters 10 the coiling apparatus and is led over suitable guiding means to the revolvable wire guide 15. As here shown, the wire at first passes over a sheave 70, then over a sheave 72, from which it passes into the rotary part 14 in line with the 15 axis of rotation of said rotary part. The rotary part 14 has a bore 14 through its sleeve 30, through which the wire passes. After passing through the bore 14, the wire runs to the sheave 45 of the revolvable wire guide 15 being guided 20 by the sheave 76 at the point where it departs from alignment with the axis of the said rotary part 14. From the sheave 45 the wire passes to the winding-on portion 12 of the drum 10, either directly or around the auxiliary roller 62. In 25 operation, the rotary-part 14 is rotated continuously (by motor 40 through shaft 38 and gears 37 and 35) carrying the wire-guide 15 with it, causing it to revolve in an orbit adjacent to and in proper position to wrap or wind the wire in 30 spirals on the winding-on portion 12 of drum 10. As the wire guide 15 winds wire around the winding-on portion 12, it pulls wire continuously from the wire-drawing machine or reel from which the supply of wire is obtained. In this winding 35 operation there is a very considerable tension produced on the wire, which is manifested as a strong pull on the drum 10 tending to rotate it.

In starting the machine an end of the wire is fastened to the drum 10 so as to be able to resist 40 the pull thereon due to the tension resulting from the rotation of the wire guide 15, or, a sufficient number of turns of wraps of the wire around the winding-on portion 12 are made, to result in sufficient friction between the wire on 45 the winding-on portion 12 of the drum, to enable the wire to resist the pull incident to the revolution of the wire guide 15 around the drum.

The flanged rollers 130 provide a means for supporting a desired number of wraps or spirals 50 of the wire on the winding-on portion 12, in a vertical type of apparatus, or otherwise, where necessary or desired.

As the wire is wound on the winding-on portion 12, the successive spirals push those ahead 55 of them. The lowermost spiral on the winding-on portion 12 is pushed or falls by gravity on to the portion 11 of the drum, and the successive spirals on the portion 11, are stopped by the shelf 109 of the detent 90, where they accumulate in a coil of the kind desired (wire-length, weight, etc.).

When the flanged rollers 130 for supporting the spirals on the winding-on portion 12 of the drum are employed, the spirals pass on to the 65 portion 11 of the drum between two of the flanged rollers 130.

When a coil of the desired kind or size is accumulated on the shelf 109, the detent 90 is moved out of engagement with the drum 10. 70 This allows the coil to drop onto the shelf 110 of the detent 92. This position is illustrated in Fig. 6 of the drawings. When the coil is dropped on to the shelf 110, the detent 90 is moved back into engagement with the drum 10, whereupon 75

the formation of a new coil on the shelf 109 begins. This position is shown in Fig. 7. While the completed coil is resting on the shelf 110, a tie 113, as a piece of wire may be fastened around 5 the coil to bind the spirals together. At the same time the strand of wire which connects the coil to the new coil may be severed, as at the point X, Fig. 7. The completed coil on the shelf 110 may then be removed by moving the detent 10 92 out of engagement with the drum 10. At this time the drum is maintained against rotation by the detent 90. When the detent 92 is moved out of engagement the coil drops or is removed from the drum, passing off the free end of the drum, 15 as shown in Figs. 1 and 8. After the completed coil has been removed the detent 92 is moved back into engagement with the drum 10. This position is shown in Fig. 9. Meanwhile the coil on shelf 109 has been forming, and when the de- 20 sired size has been reached, the detent 90 is moved out of engagement with the drum 10, and the coil falls on to the shelf 110. This position is shown in Fig. 10, and is the same position shown in Fig. 6. Figs. 6 to 10 therefore illus- 25 trate one cycle in the forming and removal of the coils, with the beginning of the next cycle (Fig. 10). All of this occurs while the wire guide 15 operates continuously to wind wire on the drum 10.

30 The coils which are removed, instead of constituting separate or complete coils, may go to form increments of a large coil, as previously described.

What is claimed is:

- 35 1. Apparatus for coiling wire and the like, comprising a vertical stationary drum, having a winding-on portion, a rotary part and a wire-guide thereon revolvable around the winding-on portion of said drum, and means for holding 40 the drum against the pull of the wire thereon tending to rotate it, characterized by said drum-holding-means comprising detents having jaws movable at substantially right angles to the axis of said vertical drum, engaging said drum at 45 points spaced apart longitudinally of the drum and at opposite sides of the drum, said spaced detents being independently movable into and out of engagement with said drum, the arrangement being such that the detent jaws may be

moved alternately into and out of such engagement, so that when the detent jaw nearest the winding-on portion of the drum is moved out of engagement the coil above it can move as far as the next detent jaw and thereafter the out-of- 5 engagement detent jaw moved back again into engagement with the drum and the succeeding detent jaw moved out of engagement with the drum, whereupon the coil which was detained by it can move along toward the end of the drum 10 and off from it, and the detent jaw moved back again into engagement with the drum.

2. Apparatus according to claim 1, wherein said detent-jaws comprise shelves on which the coils may rest while they accumulate on the 15 drum.

3. Apparatus according to claim 1, wherein said detents comprise slides having jaws and shelves, and further comprising guide-ways for said detents substantially at right angles to the 20 axis of said drum in which said detents are slideable to bring said jaws into and out of engagement with said drum.

4. Apparatus according to claim 1, further including means for retaining a number of spirals 25 of the wire on the winding-on portion.

5. Apparatus according to claim 1, further including means for retaining spirals of wire on the winding-on portion and means for adjusting the vertical position of said spiral-retaining 30 means to vary the number of spirals held in said winding-on portion.

6. Apparatus according to claim 1, wherein said detents each comprise complementary parts constructed and arranged to move into and out 35 of engagement with said drum from opposite sides thereof.

7. Apparatus according to claim 1, wherein said detents each comprise complementary jaws constructed and arranged to move into and out 40 of engagement with said drum from opposite sides thereof.

8. Apparatus according to claim 1, wherein said rotary part comprises a sleeve in line with its axis of rotation, and a bearing for said sleeve, 45 the wire passing to said wire guide through said sleeve.

CARL O. BRUESTLE.
